UNITED STATES PATENT OFFICE.

LUTHER L. BONHAM, OF KNOXVILLE, TENNESSEE.

AIR-BRAKE.

1,359,664.

Specification of Letters Patent. Patented Nov. 23, 1920.

Application filed May 16, 1919. Serial No. 297,479.

To all whom it may concern:

Be it known that I, LUTHER LAFAYETTE BONHAM, a citizen of the United States, residing at Knoxville, in the county of Knox 5 and State of Tennessee, have invented a new and useful Improvement in Air-Brakes, of which the following is a specification, reference being had to the accompanying drawing.

10 My invention relates particularly to air-brake equipment to be used on standard railway trains.

The object of the improvement is to provide for safely and practically effecting a 15 more rapid discharge or exhaust of air from the brake pipe of the train when the engineer's automatic brake valve is put into service position, in order that service application of the brakes may be made throughout 20 the train in less time than is now required for this purpose. Under present practice, during such exhausting of air from the brake pipe when the automatic brake valve is in service position, it requires a greater 25 length of time to exhaust the air from the brake pipe than is required with my invention.

As is known to those familiar with this art, such emergency application is apt to be made through a quick or abrupt transmission of pressure resembling a positive or clearly defined pulsation or throb. To illustrate, it is known that the sudden opening and closing of a quarter inch port on the 30 brake pipe of the train would cause such a 35 pulsation of sufficient force to lead to emergency application of the brakes. Hence it has been recognized as necessary to so control air above the equalizing piston and also below that piston as to avoid the transmission of pulsation or shock from the brake pipe into the triple valves and into the distributing valve or automatic control valve, if one is used. Under the construction heretofore in use the effecting of a graduation or 40 even flow of exhaust can be accomplished only through restraining the flow. This has necessitated limiting the size of the port in the service-exhaust fitting of the automatic 45 brake valve, in order to graduate or limit the flow of air from the brake pipe to the atmosphere; and this has led to making the valve leading from the lower side of the equalizing piston of a form adapted to graduate or 50 limit flow of air so as to prevent such abrupt 55 change of velocity of air flow when the valve is raised as will transmit a well defined

throb or pulsation through the brake pipe. This slow exhaustion delays the service application of the brakes.

By my improvement I provide an enlarged volume of air freely flowing from the brake pipe into the chamber below the equalizing piston so that abrupt change of density of air in said chamber is avoided. In other words, such air is made of sufficient 65 volume to cause a well graduated change of density in said chamber due to flow of air outward through the port opening of the service-exhaust fitting.

Having thus provided for reduction of 70 tendency to abrupt or spasmodic change of density in said chamber, the way has been prepared for safely and practically enlarging said exhaust port and enlarging the valve which permits air to flow to said port. 75

In the accompanying drawings,

Figure 1 is a diagrammatic view illustrating portions of an air-brake equipment for a railway train;

Fig. 2 is an elevation of the automatic 80 brake valve which forms a part of the equipment shown by Fig. 1;

Fig. 3 is a plan of the same automatic brake-valve;

Fig. 4 is a bottom view of the same valve; 85

Fig. 5 is an upright section on the line, 5-5, of Figs. 3 and 4, looking in the direction of the arrow;

Fig. 6 is an upright section on the line, 6-6, of Figs. 3 and 4, looking in the direction of the arrow. 90

Referring first to Fig. 1, A is the automatic brake valve of a form of Westinghouse air-brake equipment for trains. B is the independent brake valve. C is the 95 distributing valve. D is a reducing valve. E is a feed valve. F and G are gages. H is the main reservoir pipe. I is a pipe leading from the main reservoir pipe to the gage, F. J is a feed valve pipe leading from the feed valve, E, into the automatic brake valve. K is the governor pipe leading from the automatic brake valve to the pump governor (not shown). L is the release pipe leading from the air-brake valve to the independent brake valve, B. M is the application cylinder pipe leading from the valve, A, to the valve, B, and the valve, C. N is a gage pipe leading from the valve, A, to the gage, F, and to the equalizing reservoir, 110 O. P is a pipe leading from the pipe, Q, to the gage, G. Q is the brake pipe. R is a

pipe leading from the distributing valve, C, to the brake pipe. S is a release pipe joining the valve, B, and the valve, C. T is the brake cylinder pipe. This connects 5 with the distributing valve, C. U is a gage pipe which conveys air from the brake cylinder pipe to the gage, G.

All the parts thus far described are well known to those who are familiar with this art.

10 Referring now to Fig. 5, A¹ is the usual equalizing piston above which is the chamber, A², and below which is a chamber, A³. The stem, A⁴, extends downward into the bushing, A⁵, to form the brake-pipe exhaust 15 valve at A⁶ in the usual manner. Below said valve is the usual service-exhaust fitting, A⁷, having the exhaust port, A⁸.

While the bushing, A⁵, and the stem, A⁴, and the exhaust, A⁷, are arranged relatively 20 as has been done heretofore, I have increased the cross sectional area of the stem, A⁴, and of the interior of said bushing and of said fitting. This has been made possible by my introduction of another feature which will 25 be described farther on.

In the standard form heretofore in use, the service-exhaust fitting, A⁷, has had a port opening of $\frac{3}{16}$ of an inch. I have increased this port opening to $\frac{1}{4}$. The object 30 in using a larger port opening for the fitting, A⁷, is to exhaust the air from the brake pipe more rapidly than can be done with the ordinary equipment now in use. This faster exhaustion leads to a speedier service application of brakes throughout the train.

But, heretofore such rapid discharge of air from the fitting, A⁷, has been impracticable for the reason that a more rapid exhaust than was permitted by the small 40 port ($\frac{3}{16}$ of an inch) would lead to emergency application of the engine and train brakes while the engineer's automatic brake valve was set in service position. When, according to present practice, a partial 45 or full service application of locomotive and train brakes is desired, the automatic brake valve is put into service position. Then, in the well-known manner, air is exhausted from the chamber, A², above the piston, A¹, and from the equalizing reservoir, O, which communicates with said chamber through the pipe, N. The automatic brake valve is then placed into lap position. For a full service application of 50 the brakes, when the brake pipe pressure is 70 pounds, 20 pounds of air is exhausted from the chamber, A², and reservoir, O. The exhausting of the air from the chamber, A², permits the piston, A¹, to rise on account of the larger pressure in the chamber, A³, below the piston. Such rising of the piston opens the valve, A⁶, and allows exhaust through the exhaust fitting, A⁷.

This continues until the pressure in the 65 chamber, A³, is sufficiently reduced to cause

the remaining pressure in the chamber, A², to again drive the piston, A¹, down to normal position, the position in which the valve, A⁶, is closed.

As has already been stated, it is well-known 70 to those who are familiar with this art, that emergency application is liable to be made whenever there is a quick or abrupt transmission of pressure, resembling a positive or clearly defined pulsation, through the 75 brake pipe.

To avoid quick or abrupt changes of pressure due to exhaustion from the chamber, A³, below the piston, A¹, I have provided on or in connection with the brake pipe, Q, an 80 air reservoir, Q¹, which will contain such a quantity of air near the automatic valve as to cause such a nearly uniform delivery of air through the upper end of the brake pipe, Q, as will prevent a quick or abrupt variation 85 in pressure in the chamber, A³. In Fig. 1 of the drawings, the reservoir, Q¹, is attached to the pipe, Q, by means of a branch, Q². In Fig. 5 the reservoir, Q¹, is directly on the pipe, Q, a gap being formed in the 90 pipe and the ends of the pipe being tapped into the ends of the reservoir. As soon as the reduction of air pressure above the piston, A¹, begins, the piston is lifted by the greater air pressure below the piston. Thus 95 the valve below the piston is opened and air is exhausted through the valve and the port of the exhaust fitting, A⁷. This exhausting continues until the pressure below the piston becomes equal to the pressure above the piston. That requires a pressure reduction in 100 the entire length of the brake pipe. The amount of air required to be thus exhausted through the exhaust fitting to produce balance of pressure above and below the piston increases with increase in the length of the train; and since the length of trains is being 105 increased in practice, it becomes increasingly important to effect a more rapid exhaust from the exhaust fitting of the automatic 110 brake valve. In shop tests of my improved apparatus (in which the valve, A⁶, and the exhaust port were enlarged as above described), I connected a triple valve to the 115 brake pipe between the reservoir, Q¹, and the automatic brake valve. Then setting the automatic brake valve to service position resulted in putting the triple valve into service position and not into emergency position. That indicated that the larger volume of air 120 in the reservoir, Q¹, supplies air into the automatic brake valve in such quantity as to cause a graduated flow through the exhaust port, whereby the forming of pulsation is entirely or substantially prevented.

125 I deem it probable also that the air in the reservoir, Q¹, serves as a cushion or shock absorber for neutralizing such reduced pulsations as do extend from the automatic brake valve into said reservoir; so that my 130

improved apparatus is adapted (1) to prevent or reduce the forming of pulsation, and (2) to neutralize such pulsation as is formed and extends into the reservoir, Q¹.

5 I claim as my invention,

1. In an air brake equipment, the combination with the automatic brake valve having an enlarged exhaust port and the brake pipe leading into the chamber below the equalizing piston, of an air reservoir in communication with the brake pipe in position to readily deliver air into said chamber when the exhaust valve of the automatic brake valve is open, in order that during service 10 application abrupt changes in air density in said chamber may be prevented and in order that the transmission of shocks or pulsations through the brake pipe may be prevented, substantially as described.
- 15

2. In an air brake equipment, the combination with the automatic brake valve having an enlarged exhaust port, of a brake pipe structure leading into the chamber below the equalizing piston and being of sufficient interior capacity to contain an enlarged and sufficient volume of air to cause ready delivery of air into said chamber when the exhaust valve of the automatic brake valve is open, in order that during service 20 application abrupt changes in air density 25 in said chamber may be prevented and the transmission of shocks or pulsations through the brake pipe may be prevented, substantially as described.

In testimony whereof I have signed my name, this 3rd day of May, in the year one thousand nine hundred and nineteen.

LUTHER L. BONHAM.
